UNITED STATES PATENT OFFICE

135,030

DESIGN FOR A DISH OR SIMILAR ARTICLE

Arthur L. Harshman, Dunkirk, Ind., assignor to Indiana Glass Company, Dunkirk, Ind., a corporation of Indiana

Application December 13, 1941, Serial No. 104,619

Term of patent 7 years

To all whom it may concern:

Be it known that I, Arthur L. Harshman, a citizen of the United States and resident of Dunkirk, in the county of Jay and State of Indiana, have invented a new, original, and ornamental Design for a Dish or Similar Article, of which the following is a specification, reference being had to the accompanying drawing, forming a part thereof.

In the drawings:

I claim:

The ornamental design for a dish or similar article, substantially as shown and described.

ARTHUR L. HARSHMAN.
